UNITED STATES PATENT OFFICE.

EGMONT MAX TORMIN, OF NEWTON CENTER, MASSACHUSETTS, ASSIGNOR TO HOLTZER-CABOT ELECTRIC COMPANY, OF BROOKLINE, MASSACHUSETTS.

CENTRIFUGAL SWITCH.

1,108,088.

Specification of Letters Patent. Patented Aug. 18, 1914.

Original application filed January 27, 1912, Serial No. 673,724. Divided and this application filed July 31, 1912. Serial No. 712,504.

To all whom it may concern:

Be it known that I, EGMONT M. TORMIN, a subject of the German Emperor, and a resident of Newton Center, in the county of Middlesex and State of Massachusetts, have invented a new and useful Improvement in Centrifugal Switches, of which the following is a specification.

The present invention relates to centrifugal switches and more especially to such switches which are adapted for use with lighting machines.

In my application Serial No. 673,724, filed January 27, 1912, of which this application is a division, I have described a direct current lighting machine adapted to be driven through wide variations of speed by a motor vehicle. In machines of this character it is desirable that a certain minimum speed, such for example as two hundred revolutions per minute, be obtained before the external circuit is energized, and for this purpose I provide the centrifugally-operated switch or cut-out which forms the subject matter of the present invention.

One embodiment of my invention is illustrated in the drawings which accompany and form a part of this specification.

In the drawings—Figure 1 is a diagram showing one arrangement of circuits which may be employed when my improved centrifugal switch is used in connection with a lighting generator. Fig. 2 is a front view of the preferred form of my improved cut-out. Fig. 3 is a section taken on the line 3—3 of Fig. 2 and Fig. 4 is a horizontal section taken on the line 4—4 of Fig. 2.

In the particular drawings selected for more fully disclosing my invention, 5 represents the generator, provided with brushes 40, the winding 9 herein shown as a shunt winding, and having the switch or cut-out keyed to its shaft 1. The switch consists in the present instance of the collector hub 20 of brass or other suitable material keyed to the shaft 1 and carrying the segmental collector ring 6, secured thereto by screws 22 and shown in the present instance as made up of three segments 21, 21', 21'', each suitably insulated from the collector hub. A switch member 23 consisting of a portion of a ring is secured to the collector hub by

the screws 24 and is suitably insulated from the same. Passing through the switch member 23 is a screw 25 which clamps the inside and outside circular plate-springs 29 and 30 separated at this point by the spacing member 50, between the block 23' and said switch member, said block 23' being in electrical contact with the segment 21. Two centrifugally operated heads 26, 26 are secured to the inner spring 29 by the rivets 27 and are provided with contact plates 28, 28, which preferably are of copper, the rivets 27 passing through the plate, the spring, and the head, as shown in Fig. 2. In order to prevent friction between the springs the extremities only of the outer spring 30 may bear against the inner spring 29, and for this purpose the ends of the former are bent in radially as shown at 31, 31. A mica cover plate 32 is interposed between the cut-out and the commutator. It will be apparent that the rotation of the shaft 1 will cause the heads 26, 26 to move outwardly, and that by suitable proportionment of the springs 29, 30, the contact plates 28 can be made to bear against the interior of the segmental collector ring when any predetermined speed of rotation has been attained, and, by making electrical contact with the segments 21', 21'', short circuit the same.

Referring to the diagram shown in Fig. 1, 40, 40 represent the dynamo brushes and 41, 41 the cut-out brushes. 43 is a source of current, preferably a storage battery. 44 represents incandescent lamps, such for example, as the head-lights of an automobile. The cut-out is connected in series with the line 46, 46, as shown, and the storage battery and lamps are connected across the same. It will be obvious that the line remains open until the plates 28, 28 make contact with the ring 21 and short-circuit the segment thereof.

It will be understood that I do not limit myself to the particular embodiment of my invention which I have described and illustrated, inasmuch as various modifications may be made by those skilled in the art, both in the apparatus described and in the circuit arrangements employed therewith, that will accomplish the objects of my invention in substantially the same manner.

I claim:

1. In a dynamo electric machine, a cut-out comprising a collector hub mounted on the axle of the machine, a collector ring comprising a plurality of segments secured to said hub, centrifugally-operated contact members arranged to make contact with the interior of said collector ring when the machine attains a predetermined speed, but normally out of contact therewith, and brushes constantly maintained in electrical contact with the exterior of said ring.
2. In a dynamo electric machine, a cut-out comprising a collector hub mounted on the axle of the machine, a collector ring comprising a plurality of segments secured to said hub, spring-retracted centrifugally-operated contact members arranged to make contact with the interior of said collector ring when the machine attains a predetermined speed, but normally out of contact therewith, and brushes constantly maintained in electrical contact with the exterior of said ring.
3. In a dynamo electric machine, a cut-out comprising a collector hub mounted on the axle of the machine, a collector ring comprising three segments secured to the hub, two centrifugally-operated contact members arranged to make contact respectively with two of said segments and means for electrically connecting said contact members with the third segment.
4. In a dynamo electric machine, a cut-out comprising a collector hub mounted on the axle of the machine, a collector ring comprising a plurality of segments secured to said hub, centrifugally-operated contact members arranged to make contact with the interior of said collector ring when the machine attains a predetermined speed, but normally out of contact therewith, a circular plate-spring normally tending to retract said

contact-members, and brushes constantly maintained in electrical contact with the exterior of said ring.

5. In a dynamo electric machine, a cut-out comprising a collector hub mounted on the axle of the machine, a collector ring comprising a plurality of segments secured to said hub, centrifugally-operated contact members arranged to make contact with the interior of said collector ring, a circular plate-spring normally tending to retract said contact members, and a second circular plate-spring inclosing the first spring and having its extremities only in contact therewith.

6. In a dynamo electric machine, a cut-out comprising a collector hub mounted on the axle of the machine, a collector ring comprising a plurality of segments secured to said hub and normally insulated from each other, centrifugally-operated means for short-circuiting said segments when the machine attains a predetermined speed, and brushes constantly maintained in electrical contact with the exterior of said ring.

7. In a dynamo electric machine, a cut-out comprising a collector ring, said collector ring consisting of a plurality of segments mounted on and rotating with the axle of the machine, centrifugally-operated contact members arranged to make contact with the interior of said ring when the machine attains a predetermined speed, but normally out of contact therewith, and brushes making contact with the exterior of said ring.

In testimony whereof, I have hereunto subscribed my name this 27th day of July 1912.

EGMONT MAX TORMIN.
